Adolph Faller

United States Patent Office.

ADOLPH FALLER, OF NEW YORK, N. Y.

Letters Patent No. 80,159, dated July 21, 1868.

IMPROVED LOUNGE, BUREAU, AND TABLE.

The Schedule referred to in these Letters Patent and making part of the same.

TO ALL WHOM IT MAY CONCERN:

Be it known that I, ADOLPH FALLER, of the city and State of New York, have invented and made a certain new and useful Improvement in Lounges, consisting in a combined Lounge, Bureau, and Table; and I do hereby declare the following to be a full, clear, and exact description of the said invention, reference being had to the annexed drawing, making part of this specification, wherein—

Figure 1 is a plan of said combined lounge, table, and bureau, and

Figure 2 is an elevation of the same.

Similar marks of reference denote the same parts.

The nature of my said invention consists in a combined lounge, bureau, and table, so constructed and arranged that the table is conveniently located for the use of a person lying upon the lounge, and the drawers composing the bureau are easily reached when either in a lying or sitting posture, by which arrangement there is no waste of space in a room, as is usual with lounges of ordinary construction, and the parts are in a convenient position for use by an invalid or by any other person.

In the drawing, *a* represents the usual seat portion of the lounge, *b* is the back of the same, and *c* is the inclined cushioned end, that comes against the bureau portion of the lounge, in which are drawers *d d*, and above which is the table *e*.

f f are drawers in the lounge below the seat portion.

It will be apparent that the drawers *d d* and *f*, and table *e*, are in a position convenient to a person reclining or sitting upon the lounge, and that there is not any loss of room by the inclination and curvature of the arm as usual.

What I claim, and desire to secure by Letters Patent, is—

The combined lounge, table, and bureau specified, the same being formed with the inclined cushioned end *c* against the bureau portion, with the table *e* above the bureau, and with drawers in and below such lounge, substantially as set forth.

In witness whereof, I have hereunto set my signature, this 6th day of June, A. D. 1868.

ADOLPH FALLER.

Witnesses:

CHAS. D. SMITH,
GEO. T. PINCKNEY.
